UNITED STATES PATENT OFFICE.

FRANK L. ORDWAY, OF SALEM, MASSACHUSETTS, ASSIGNOR TO PARKER BROTHERS, INC., OF SALEM, MASSACHUSETTS, A CORPORATION OF MAINE.

ANCHORING DEVICE FOR TABLE-TENNIS NETS AND THE LIKE.

1,250,634.

Specification of Letters Patent. Patented Dec. 18, 1917.

Application filed January 22, 1917. Serial No. 143,732.

To all whom it may concern:

Be it known that I, FRANK L. ORDWAY, a citizen of the United States, and resident of Salem, in the county of Essex and Commonwealth of Massachusetts, have invented an Improvement in Anchoring Devices for Table-Tennis Nets and the like, of which the following description, in connection with the accompanying drawings, is a specification, like characters on the drawings representing like parts.

This invention relates to anchoring means, the illustrated embodiment being an adjustable support or post adapted to be clamped to the margin of a supporting member such as a table and designed to hold stretched thereacross the net used in the game of table tennis.

My invention will best be understood by reference to the following description taken in connection with the accompanying drawings, wherein,

Figure 1 is an elevation of a table tennis net supported in position on a table by two anchoring devices embodying my invention;

Fig. 2 is a side elevation on a larger scale of one of the devices shown in Fig. 1; and

Fig. 3 is an end elevation of the same viewed from the right.

Referring to the drawings, in Fig. 1 I have shown two devices 5 embodying my invention secured to the margins of a table 7 and having stretched between them a net 9 such as is used in the game of table tennis.

Referring to Figs. 2 and 3, wherein one of the devices 5 is illustrated on a much larger scale, the embodiment here shown comprises an angular member 11 which may be constructed of so-called flat wire or other material preferably having a certain amount of resiliency. One leg 13 of the angular member forms a base part which is adapted to rest upon a supporting member such as the table 7 in the manner illustrated in Fig.

1. The other leg 15 forms an upright which is an example of suitable provision for attaching the device to be anchored, such as the tennis net, to the anchoring means. Herein I have shown the upright as carrying eyes 17 to which the devices to be anchored may be secured.

Coöoperating with the angular member 11 is another angular member 19 which may likewise be constructed of flat wire and is conveniently formed with the central por-

tion 21 and oppositely directed terminal portions 23 and 25. The terminal portion 23 forms a foundation to which the base part 13 of the member 11 may be secured. The other terminal portion 25 in coöperation with the central portion 21 and the free end of the base part 13 forms a jaw which in the embodiment shown opens away from the angle of the part 11 and which is adapted to receive the margin of the supporting member, the parts 21 and 25 being fitted about the same. Desirably, suitable clamping means such as the screw 27 are associated with the part 25 to clamp the anchoring device upon the supporting member.

To permit adjustment of the anchoring device to different positions the member 11 is made to slide relatively to the member 19. Herein a sliding connection is provided between the base part 13 and the foundation portion 23 by means of two rings 29 closely encircling the same maintaining them in alinement and holding them together. The two rings are one example of means for connecting the parts along a substantial length as distinguished from a connection at a single point which would permit pivoting. It

is apparent that the base part 13 may be adjusted along the foundation part 23 so as to vary the position of the upright relative to the jaw which receives the supporting member. For example in Fig. 1 I have shown the two supports in different positions of adjustment. When the device is anchored to the upright 15 so as to apply tension thereto, a turning moment is developed in the member 11 and the left-hand ends of the parts 13 and 23 tend to spread apart, as indicated in an exaggerated manner in Fig. 1. Since these two parts are connected along a substantial length, the result of this action is to cause binding of the connection which will effectually hold the member 11 in its adjusted position as regards the member 19.

It will, furthermore, be noted that the tipping tendency tends to depress the right-hand end of the member 13 and thus to close upon the supporting member the jaw of which it forms a part. Conversely to this action the form of the member 19, in the embodiment of the invention illustrated, is such that when the jaw is spread, for example by manipulation of the clamping device 27, the connection between the parts 13 and 23 will bind because they tend

to spread apart at their right-hand end in Fig. 2.

As illustrated best in Fig. 2 I may provide parts which will come in contact with the table 7 or other supporting member with suitable pads 31.

It will thus be seen that I have provided a substantial and easily constructed device of the kind described of which the member 13 may, as herein shown, form a part of the jaw which receives a supporting member such as the table 7. The structure is such that it may readily be adjusted when the parts are in the normal unstrained position illustrated in Fig. 2, but which automatically locks the parts in their adjusted position when in use.

Having thus described one typical embodiment of my invention in considerable detail, what I claim and desire to secure by Letters Patent is:

1. An anchoring means for securing table tennis nets or the like, comprising an angular member having a leg forming a base part and a leg forming an upright having provision for attachment of the anchored device thereto, and a second angular member attached to said base part and coöperating therewith to form a jaw adapted to receive a supporting member and opening away from the angle of the first angular member, said members being slidably connected together whereby tension on said upright will tend both to close said jaw and to cause the connection to bind.

2. An anchoring means for securing table tennis nets or the like, comprising two members slidably connected and coöperatively forming a jaw adapted to receive a supporting member, one of said members having an attaching part for securing the anchored device thereto situated to develop a turning moment of one of said members to cause the connection between them to bind.

3. Anchoring means for table tennis nets and the like, comprising a member constructed to be fitted to the margin of a support and presenting a foundation part, a

second member having a base part slidably secured to said foundation part along a substantial length and also having a part which has provision for attachment of a tension member thereto and is so arranged that tension thereon may cause binding of the connection between said members.

4. A support for a table tennis net, comprising a measurably resilient angular member providing a base portion and an upright, and a coöperating member having a central portion and oppositely directed terminal portions, one said terminal portion being slidably connected to said base member and the other carrying a clamping device.

5. Anchoring means for table tennis nets and the like, comprising a member having a base part adapted to rest on a supporting member and having provision for attachment of the anchored device, and a coöperating member having a central portion and oppositely directed terminal portions, one said terminal portion being slidably connected to said base part, the other terminal portion in coöperation with said central portion and said base portion forming a jaw to receive a margin of the supporting member, spreading of said jaw serving to cause binding of the connection between said first terminal portion and said base part.

6. Anchoring means for table tennis nets and the like comprising an angular member providing a base portion adapted to rest on a supporting member and an upright and a coöperating member having a central portion and oppositely directed terminal portions, one said terminal portion being secured to said base portion and the other in coöperation with said central portion and base portion forming a jaw to receive the margin of the supporting member, the securing devices being thereby disposed externally of said jaws and out of contact with said member.

In testimony whereof, I have signed my name to this specification.

FRANK L. ORDWAY.
